UNITED STATES PATENT OFFICE

169,985

COMBINED LAMP AND CONTAINER OR THE LIKE

John B. Musacchia, Brooklyn, N. Y., and
Raymond Nicyper, Bergenfield, N. J.

Application January 29, 1953, Serial No. 23,338

Term of patent 14 years

(Cl. D48—4)

To all whom it may concern:

Be it known that we, John B. Musacchia, a citizen of the United States of America, residing at Brooklyn, in the county of Kings and State of New York, and Raymond Nicyper, a citizen of the United States of America, residing at Bergenfield, in the county of Bergen and State of New Jersey, have invented a new, original, and ornamental Design for a Combined Lamp and Container or the like, of which the following is a specification, reference being had to the accompanying drawing, forming part thereof.

Fig. 1 is a front perspective view of a combined lamp and container showing our new design;

Fig. 2 is a front elevational view thereof; and

Fig. 3 is a side elevational view.

We claim:

The ornamental design for a combined lamp and container or the like, as shown.

JOHN B. MUSACCHIA.
RAYMOND NICYPER.
